MULTIPLE-FOCUS X-RAY TUBE

James F. Lee, Palo Alto, Calif.

Application December 4, 1934, Serial No. 755,874

10 Claims. (Cl. 250—35)

This invention relates to multiple-focus X-ray tubes and its primary object is to provide an effective safeguard against mistakes by the technician with respect to the focal-spot setting.

5 A further object is to facilitate initial adjustments of the several focal-spot areas during the course of manufacture so that all tubes of a given designation will have identical focal-spots.

There are two general types of multiple-focus 10 X-ray tubes, namely: the single filament and double filament types, respectively. The present invention is applicable to and is herein described with reference to both those types of tubes.

Both possess great advantage over single-focus 15 tubes; but their commercial success has, in the past, been somewhat hampered by their greater susceptibility to mistakes on the part of the technician with respect to the focal-spot settings—a single mistake of that character sometimes being enough to destroy the usefulness of a costly 20 tube.

X-ray technicians are, as a rule, intelligent and alert people and when one makes a mistake as to a focal-spot adjustment it is not due to carelessness but to faulty memory or confusion. 25 Hence if some means be provided, as is here done, which will inform the technician clearly and unmistakably as to the adjustment of the tube, it is to be expected that errors of the kind here 30 dealt with will become exceedingly rare.

With an X-ray tube equipped according to the present invention, adjustment of the focal-spot area is effected by means of a key which must be inserted in a keyhole provided in the tube in 35 order to obtain a focal-spot smaller than the largest spot which the tube is designed to produce. For a two-focus tube only one key would be needed; but for tubes intended to operate on a larger number of focal-spot areas, a proportionately larger number of keys are required. 40 The four-focus tube here selected for illustration requires three keys. Each key, preferably, is provided with a large head or flag bearing some suitable notation such as a large numeral and, preferably, is also identified by some distinguishing color. When in use, the key is so situated as to 45 be easily visible and prominent; and the head or flag and the notation thereon are so large as to be readable without difficulty from a considerable distance. The tube is so designed and constructed that it automatically restores itself to the broadest focal-spot setting when a key is withdrawn and it is, therefore, impossible to mistakenly imagine that the tube, when within view, 50 is set to produce the broadest focal-spot where-

as, in fact, it is not. Likewise, only gross negligence or irresponsibility could account for failure to distinguish between the different keys.

The present application emphasizes more particularly the single filament type of multiple-focus X-ray tube, which is usually designed to provide four focal-spot settings; and the mechanism herein illustrated and described (except that of Fig. 12) is intended to be embodied in an X-ray tube such as that described and claimed 10 in the co-pending application of James F. Lee, Serial Number 721,142, filed April 18, 1934, to which reference is here made for a description of the focus-adjusting mechanism.

In the drawing which accompanies this specification:

Fig. 1 is an elevational view, partly in section, of the end portion of the cathode arm of a single filament multiple-focus tube illustrating, inter alia, the screw plug for making electrical connections, the re-entrant stem which forms a support for the cathode and focus-adjusting mechanism, the operating lever by means of which the focus-adjusting mechanism is manipulated and the head or flag of one of the keys which function to operate the focus-adjusting mechanism and to apprise the operator of the focal-spot setting;

Fig. 2 is a cross-sectional view taken along the line 2—2 of Fig. 1;

Fig. 3 is a view taken along the line 3—3 of Fig. 1 showing the key-operated mechanism with a key inserted;

Fig. 4 is an endwise view of the tube;

Fig. 5 is an enlarged cross-sectional view taken 35 along the line 5—5 of Fig. 3;

Fig. 6 is a longitudinal sectional view taken along the line 6—6 of Fig. 3;

Fig. 7 is a fragmentary view taken along the line 7—7 of Figs. 1 and 3;

Figs. 8, 9 and 10 are side-elevational views of three keys, each of which is designed to operate the focus-adjusting mechanism to bring about a certain predetermined focal-spot adjustment;

Fig. 11 is a cross-sectional view along the line 45 11—11 of Fig. 8; and

Fig. 12 is a combined structural and diagrammatic illustration of the manner of applying the present invention to a two-filament two-focus X-ray tube.

A complete multiple-focus X-ray tube of the single filament type comprises, as its principal constituents, an evacuated glass envelope enclosing an anode or target together with an electron-emissive cathode, an adjustable focus-

ing shield or shields and a focus-adjusting mechanism operable to bring about suitable relative movements between the cathode and the focusing shield or shields whereby the size of the focal-spot is rendered variable at the will of the operator. The manner of operation of high vacuum hot cathode X-ray tubes, of which genus the tube of the present invention is a species, is too well known to require explanation here; and the focus-adjusting mechanism intended to be utilized in conjunction with the present invention is fully described in the previously identified Lee application. It is, therefore, considered unnecessary in the present case to illustrate and describe an entire X-ray tube or an entire focus-adjusting mechanism. Hence, all that is shown in the drawing is a portion of the cathode arm structure and a portion of the focus-adjusting mechanism including the key-operated device through which the focus-adjusting mechanism is manipulated and controlled and which constitutes the subject matter of this invention.

The showing of Fig. 1 is of a portion of the cathode arm, so called, that is, of the cathode end of an X-ray tube which, in a bulb type tube would be an arm. Many X-ray tubes nowadays have no bulbous mid-portion and therefore, accurately speaking, no cathode arm. That term, however, is well understood in the art and is convenient to define that portion of the tube which includes the cathode and cathode terminal contacts even though the tube may be of the straight cylindrical type having no bulbous portion. If that term is used hereafter in this specification or any of the appended claims its broader significance is intended.

The evacuated cylindrical glass envelope 13 has a tubular glass re-entrant stem 14 which is integral with the envelope. To the right hand end 40 of envelope 13 is secured a metal cap consisting of a tubular sleeve 15 and a screw threaded contact plug 16—these parts being separable and held together by screws or any other appropriate fastening means.

45 To the extreme inner end of the re-entrant stem 14 is attached what may for convenience be called the cathode head. This includes a flexible thin metal diaphragm 17 which is cup-shaped and sealed at its periphery to the inner end or lip of the re-entrant stem. This diaphragm serves as a vacuum-tight medium for the transmission of mechanical motion from the exterior to the evacuated interior of the envelope whereby the operator is enabled to manipulate the focus-adjusting mechanism so as to vary the size of the focal-spot.

The cathode head comprises, in addition to diaphragm 17, an electron-emissive cathode, suitable focusing elements or shields and a focus-adjusting mechanism including a metal tube 18 and tubular glass extension 19, which mechanism is capable of translating the simple motion of an operating lever into appropriate movements of the focusing elements—all of which is fully described in applicant's above-identified co-pending application.

Inasmuch as the cathode head structure of the present case is identical with that of the aforementioned co-pending application, it is considered unnecessary to repeat the disclosure here beyond showing enough of the structure to fully illustrate the manner of applying the present invention.

75 As explained in applicant's co-pending case,

the metal tube 18 is secured by welding or otherwise to the diaphragm 17, through the radial center of which it extends, and this tube functions as an operating lever having its pivotal point or fulcrum at the point of juncture with the diaphragm. The flexibility of the diaphragm permits the operating lever to rotate about it as a fulcrum sufficiently for the purpose. 5

Glass tube 19 is sealed to the outer end of metal tube 18 and serves as an extension thereof. Tubes 18 and 19, conjointly, serve not only as an operating lever but as a medium for evacuating the envelope—the outer end of tube 19 being drawn to a point and sealed off after completion of the pumping operation as indicated at 15 19a in Fig. 1. In Fig. 6 tube 19 is not shown sealed off because to have done so would have obscured the showing of retracting spring 21.

Viewed endwise, as per Fig. 3, the free end of the operating lever (tube 19) traverses an arcuate path indicated by the dot and dash line 25 and it is engaged by a loop formed in member 20 which is pivoted at 26 and provided with a cam follower in the form of a roller 22 which is adapted to be actuated by a key 24 when the latter is inserted in the key guide 23 as shown in Fig. 3.

Key guide 23 is made of a piece of metal tubing slotted on one side and cut back to provide clearance for roller 22 and the enlarged loop portion of member 20 in their respective retracted positions. Member 20 is engaged by a hair pin type wire retracting spring 21 which is secured at one end to sleeve 15.

An annular plate 27 is fastened inside sleeve 35 15 and forms a support for pivot 26; and the tubular key guide 23 is brazed or otherwise secured at its ends to the inside surface of sleeve 15.

Fig. 7 shows the keyhole as viewed from the exterior of the tube and Figs. 8, 9 and 10 are side elevational views of three keys, each of which corresponds to a different focal-spot setting. The key shown in Fig. 8 is that of Fig. 3 and is the one which affords the maximum movement of the operating lever and consequently the smallest focal-spot. This is ordinarily the number 1 key. The other two keys, Figs. 9 and 10, respectively, afford successively smaller movements of the operating lever and they correspond to two intermediate sized focal-spots. The latter keys should bear notations "2" and "3" respectively for identification—those being the numbers commonly assigned to the intermediate focal spots in a four-focus tube.

With no key inserted the end of the operating lever is held by spring 21 in its furthestmost right hand position (as viewed in Fig. 3)—which position corresponds to the broadest focal spot. Fig. 3 has been drawn with the number 1 key inserted and the operating lever is therefore shown in its furthestmost left hand position.

It will be apparent that with no key inserted the tube is always adjusted to meet its maximum rating and no damage will be done as the result of a technician's faulty memory—which would be likely to happen if the tube did not automatically restore itself to the broadest focal-spot setting upon the withdrawal of a key. If the tube is adjusted for any of the smaller focal-spots one of the keys is necessarily in place and there is no excuse whatever for a technician making a mistake as to the focal-spot setting because its number stands out boldly on the head of the key.

Member 20 can conveniently be made from a 75

long metal strip bent as shown in Fig. 3. See also the enlarged cross-sectional view, Fig. 5. The extension 20a is designed to engage key guide 23 and act as an adjustable stop. By bending this extension the area of the broad focal-spot can be adjusted. This is done in the course of manufacture of the tube; but such an adjustment can also be made afterward if need be.

The device which has been described is not only well adapted to fulfill its primary function which is to prevent mistakes as to focal-spot settings, but it offers a very substantial advantage in that it permits of a simple and easily performed initial determination of the focal-spot areas during manufacture of the tube so as to take care of unavoidable manufacturing variations. All tubes of a particular designation must have identical focal-spots; otherwise individual rating charts would have to be prepared and supplied with each tube—an intolerable condition. With the arrangement described any deviation from standard in the area of the broad focal-spot can be corrected by adjusting the extension 20a and similar deviations from standard in the other focal-spot sizes can be corrected by cutting the cam surfaces of the keys to allow for the errors noted.

It will be obvious that an increased number of focal-spot sizes can be provided for by increasing the number of keys and that the sizes of the focal-spots can be whatever is specified between the maximum and minimum limits of the tube.

Fig. 12 illustrates how the key-operated safety provision can be applied to a two-filament X-ray tube. Here a pivoted switch blade or contact arm 37 is substituted in place of member 20. This is provided with a cam follower 28 which engages a key 29. The two filamentary cathodes are indicated by reference numerals 30 and 31; and conductors 32 and 33 lead to the filament current source. With the key inserted as shown, contact arm 37 engages contact spring 34 and a circuit is completed through cathode 30. When the key is withdrawn contact arm 37 is moved by its retracting spring 35 out of engagement with contact spring 34 and into engagement with contact spring 36. This completes a circuit through cathode 31. The key is, of course provided with a large head or flag bearing an appropriate notation as in the previous case. If cathode 31 is the one corresponding to the broad focal-spot, it follows that the tube is always set for the broad focal-spot when the key is withdrawn.

What is claimed is:

1. The combination in a multiple-focus X-ray tube of focal-spot adjusting means including a key-operated device and an operating key therefor, said device being operable automatically, when not influenced by said key, to cause the X-ray tube to be adjusted to produce a relatively broad focal-spot and to hold the tube in that adjustment, said key being operable to actuate said device and thereby cause the X-ray tube to be adjusted to produce a relatively fine focal-spot.

2. The combination in a multiple-focus X-ray tube of focal-spot adjusting means including a key-operated device and an operating key therefor, said device being operable automatically, when not influenced by said key, to cause the X-ray tube to be adjusted to produce a relatively broad focal-spot and to hold the tube in that adjustment, said key being operable to actuate said device and thereby cause the X-ray tube to be adjusted to produce a relatively fine focal-spot, said key having a head of substantial size which is adapted to be observed by the operator when

the key is in use, said head having a visible indicator corresponding to the focal-spot adjustment of the tube.

3. The combination in a multiple-focus X-ray tube of focal-spot adjusting means including a key-operated device and an operating key therefor, said device comprising a pivoted member which is rotatable about its pivot, and a spring operable, whenever said member is not influenced by said key, to move said member into a position wherein it causes the X-ray tube to be adjusted to produce a relatively broad focal-spot and to hold the tube in that adjustment, said key being operable to actuate said pivoted member and thereby cause the X-ray tube to be adjusted to produce a relatively fine focal-spot.

4. The combination in a multiple-focus X-ray tube having an evacuated envelope, of focal-spot adjusting means including an operating lever extending from the evacuated interior of said envelope to the exterior thereof, a spring operable to actuate said operating lever and to yieldably hold said lever in a position corresponding to the broadest focal-spot adjustment of the tube, and a key operable to move said lever out of the aforementioned broad focal-spot position against the action of said spring into another position corresponding to a finer focal-spot adjustment.

5. The combination in a multiple-focus X-ray tube having an evacuated envelope, of focal-spot adjusting means including an operating lever extending from the evacuated interior of said envelope to the exterior thereof, a spring operable to actuate said operating lever and to yieldably hold said lever in a position corresponding to the broadest focal-spot adjustment of the tube, a key-guide adjacent said lever, and a key operable, when inserted into said key-guide, to move said lever out of the aforementioned broad focal-spot position against the action of said spring into another position corresponding to a finer focal-spot adjustment.

6. The combination in a multiple-focus X-ray tube having an evacuated envelope, of focal-spot adjusting means including an operating lever extending from the evacuated interior of said envelope to the exterior thereof, a pivoted member engaging said operating lever, a spring operable to move said member and operating lever about the fulcrum of said pivoted member to one extreme position corresponding to a relatively broad focal-spot setting of the tube, a key-guide adjacent said member and a key, operable, when inserted into said key-guide, to move said member together with said operating lever against said spring into another position corresponding to a finer focal-spot adjustment.

7. The combination in a multiple-focus X-ray tube having an evacuated envelope, of focal-spot adjusting means including an operating lever extending from the evacuated interior of said envelope to the exterior thereof, a sleeve carried by said envelope adjacent the exterior free end of said operating lever, a pivoted member carried by said sleeve and engaging said operating lever, a spring carried by said sleeve and arranged to press upon said member, thereby normally causing said operating lever to be yieldably held in a position corresponding to the broadest focal-spot the tube is designed to produce, a key-guide carried by said sleeve adjacent said member and having an opening to permit protrusion of a key therefrom into engagement with said member, and a key adapted to be inserted into said key-guide and, when so inserted, to move said member about

its pivot together with said operating lever against the opposing pressure of said spring into a position corresponding to a finer focal-spot adjustment, said key having a head of substantial size 5 which is adapted to be observed by the operator when the key is in use, said key-head bearing a visible notation corresponding to the focal-spot adjustment of the tube.

8. The combination with a multiple-focus X-ray tube having means susceptible to manual control for varying the area of the focal-spot, of a key operable upon said means to effect variation of the focal-spot area, said key being separable from the tube and having a head of substantial size 10 which is adapted to be observed by the operator when the key is in use, said head bearing a visible notation corresponding to the focal-spot adjustment of the tube.

9. The combination with a multiple-focus X-ray tube having means susceptible to manual control for varying the area of the focal-spot, of a 15 plurality of keys operable individually upon said

means to effect variation of the focal-spot area, said keys being separable from the tube and each having a head of substantial size which is adapted to be observed by the operator when the key is in use, said key-heads each bearing an individual 5 visible notation corresponding to a particular focal-spot adjustment, each of said keys being designed to adjust the focal-spot to a predetermined area which differs from that of each of the others of said keys.

10. The combination in a multiple-focus X-ray tube having a plurality of cathodes each of which is adapted to produce a focal-spot of different area respectively, of a key-operated device for selectively closing a circuit through said 15 cathodes individually, said device including a switch member having a plurality of operating positions in each of which it closes a circuit through one of said cathodes individually, and a key operable to move said switch member from 20 one of its operating positions to another.

JAMES F. LEE.
